Des. 222,363
Patented Oct. 19, 1971

222,363

DECORATIVE HANGING INCLUDING SKELETAL FRAMEWORK

Clifton Bullard, 310 Prescott Place,
Plainfield, N.J. 07063

Filed Apr. 6, 1970, Ser. No. 22,257

Term of patent 14 years

Int. Cl. D11—04

U.S. Cl. D29—1

The figure is a side elevational view of a decorative hanging including skeletal framework showing my new design; the side opposite that shown being substantially similar thereto.

I claim:

The ornamental design for a decorative hanging including skeletal framework, substantially as shown and described.
